United States Patent Office

Des. 229,399

Patented Nov. 27, 1973

229,399

TIRE

James J. Martell, Akron, and James A. Stevens, Mogadore, Ohio, assignors to The Goodyear Tire & Rubber Company, Akron, Ohio

Filed Aug. 21, 1972, Ser. No. 282,212

Term of patent 14 years

Int. Cl. D12—15

U.S. Cl. D12—145

The figure is a perspective view of a tire showing our new design, it being understood that the design is repeated throughout the circumference of the tire, the opposite side being substantially the same as that shown.

We claim:

The ornamental design for a tire, substantially as shown and described.
